Primary Examiner — Michelle E. Wilson*Assistant Examiner* — Clese Moore, Jr.**CLAIM**

The ornamental design for a shock-absorbing seat post as shown and described.

DESCRIPTION

FIG. 1 is a front-right-top perspective view of the shock-absorbing seat post showing my new design;
 FIG. 2 is a front elevational view thereof;
 FIG. 3 is a rear elevational view thereof;
 FIG. 4 is a left side elevational view thereof;
 FIG. 5 is a right side elevational view thereof;
 FIG. 6 is a top plan view thereof;
 FIG. 7 is a bottom plan view thereof; and,
 FIG. 8 is a perspective view from another angle of view thereof.

The broken lines in the FIGS. 1-8 illustrate portions of the shock-absorbing seat post which form no part of the claimed design.
